MULTIPLE-SPEED DRILL PRESS

Fred L. Nichols, Minneapolis, Minn.

Application April 8, 1950, Serial No. 154,749

6 Claims. (Cl. 74—217)

1

My invention relates generally to drill press structure and more specifically to speed-change mechanism for drill presses.

Heretofore, a pair of stepped-cone pulleys connected by an endless belt has been utilized to effect changes in the speed of rotation of a drill bit-equipped spindle in drill presses. This arrangement permits but a relatively few different rates of rotary speed of the spindle, and the correct drilling speed for a particular drilling operation is not often achieved. The principal object of my invention is, therefore, the provision of means whereby a greater number of drill speeds may be obtained in a drill press of the above type.

Another highly important object of my invention is the provision of means whereby a drill as set forth may be operated in a plurality of speed ranges, the different speeds within one range being faster or slower than the several drill speeds within another range.

Another object of my invention is the provision of a speed-change mechanism which may be readily adapted for use on a conventional drill press.

Another object of my invention is the provision of speed-change mechanism as set forth in which transfer of power to the drill spindle between different speed ranges may be quickly and easily accomplished.

Still another object of my invention is the provision of novel clutch means for frictionally locking the above transmission mechanism in a predetermined speed range.

A still further object of my invention is the provision of speed-change mechanism of the above type which is relatively simple and inexpensive to produce and install, and which is efficient and durable in use.

Other highly important objects and advantages of my invention will become apparent from the following detailed specification, appended claims, and attached drawings.

Referring to the drawings, wherein like characters indicate like parts throughout the several views:

Fig. 1 is a view in side elevation showing a drill press built in accordance with my invention, some parts being broken away and some parts shown in section;

Fig. 2 is an enlarged transverse section taken substantially on the line 2—2 of Fig. 1;

Fig. 3 is a fragmentary axial section taken on the line 3—3 of Fig. 1, on an enlarged scale; and

Fig. 4 is a fragmentary section taken on the line 4—4 of Fig. 3.

Referring with greater detail to the drawings, a drill press 1 is shown as comprising a base 2, a supporting post or column 3, a work-supporting table 4 mounted for vertical movements on the

column 3 and a drill head structure 5. The column 3 is rigidly mounted in the base 2 and extends upwardly through a mounting boss integrally formed with the table 4. A clamping screw 7 working through the boss 6 and engaging the column 3 locks the table 4 in any desired set position with respect to the base 2 and the head structure 5. Means for raising and lowering the table 4 comprises a gear rack 8 secured at its lower end to a collar 9 which encircles the lower end portion of the column 3 and is supported from the base 2 by suitable anti-friction bearings 10. A housing or the like 11 is secured to the boss 6 and provides a bearing for a shaft 12 upon which is rigidly mounted a pinion 13 and a worm gear 14. The pinion 13 has meshing engagement with the gear rack 8 and the worm gear 14 meshes with a worm 15 journaled in the housing 11. A shaft portion of the worm 15 extends outwardly of the housing 11 and is rigidly secured to a crank or the like 16 which, when the clamping screw 7 is loosened, may be operated to raise or lower the table 4. When the locking screw 7 is loosened, the table 4 may be moved circumferentially about the column 3, the rack 8 likewise moving about the column 3 by reason of the mounting of the collar 9.

The head structure 5 includes a rear portion 17 which encompasses the upper end portion of the column 3 and is locked in place by the conventional lock bolt 18. At its forward end, the head structure 5 is formed to provide a generally cylindrical guide member 19 in which is slidably mounted for axial movements a quill 20. The quill 20 is of conventional design and is adapted to be moved vertically in the guide member 19 by manipulation of a multi-spoked elevating member 21 rotatably mounted in the head structure 5 and having rack and pinion engagement, not shown, with the quill 20 in the conventional manner. The customary locking lever for the quill 20 is indicated at 22.

The rear-end portion 17 of the head structure 5 is provided with a laterally outwardly projecting lug 23 which is screw-threaded to receive an adjustment screw 24, the lower end of which has abutting engagement with annular plate 25 as indicated at 26. The annular plate 25 is supported by a fixed collar 27 on the column 3 through the medium of anti-friction bearings or the like 28. When the locking bolt 18 is loosened, the head structure 5 may be raised or lowered with respect to the base 2 by manipulation of the adjustment screw 24; or the head structure 5 may be rotated about the axis of the column, the weight thereof being supported on the bearings 28 through the screw 24 and the annular plate 25.

A rotary spindle 29 extends axially through the vertical quill 20 and is journaled in the opposite

end portions thereof by means of anti-friction bearings 30, one of which is shown. The spindle 29 is locked against axial movements with respect to the quill 28 in the conventional manner but is movable therewith axially of the guide member 19. The spindle 29 extends vertically above the quill 28, the upper end portion thereof being splined as indicated at 31.

Suitably mounted on the head structure 5 is a vertically disposed arm 32 to which is rigidly secured a pair of vertically spaced bearing brackets 33 and 34. The brackets 33 and 34 extend laterally outwardly toward and intersect the axis of the spindle 29. At their outer ends, the brackets 33 and 34 are provided with anti-friction bearings 35 in which is journalled a tubular sleeve 36, radially outwardly spaced from and concentric with the spindle 29. At its upper end, the sleeve 36 is provided with an enlarged head or clutch element 37 having a plurality of teeth 38 which project axially outwardly of the upper end of the sleeve 36 and the side or working faces of which diverge in a direction axially outwardly of the sleeve 36 for a purpose which will hereinafter become apparent. Rotary motion is imparted to the sleeve 36 by an electric motor or the like 39, the drive shaft 40 of which extends in spaced parallel relation to the axis of the sleeve 36. An endless V-belt 41 runs over cooperating steps on a pair of stepped-cone pulleys 42 and 43 the former of which is mounted on the sleeve 36 and secured for rotation therewith by a pair of set screws or the like 44, and the latter of which is rigidly mounted on the motor shaft 40 in any suitable manner. The speed of rotation of the sleeve 36 is varied by shifting the belt 41 from one pair of cooperating steps on the cone pulleys 42 and 43 to selected other cooperating steps thereof. It will be seen by reference to Fig. 1 that the motor 39 is hingedly mounted to the rear-end portion 17 of the head structure 5, as indicated at 45 to expedite movement of the V-belt 41 from one pair of steps of the cone pulleys to another pair thereof.

Rotary motion is imparted to the spindle 29 from the pulley 42 by mechanism including a shiftable clutch member 46 which is splined to cooperate with the splined portion 31 of the spindle 29. The shiftable clutch member 46 comprises a pair of abutting sleeves 47 and 48 and a shifter collar 49 which encompasses the abutting end portions of the sleeves 47 and 48 and is rigidly locked thereto by set screws or the like 50. The shiftable member 46 is mounted for rotary and axial sliding movements in spaced anti-friction bearings 51 that are contained in the outer ends of spaced brackets 52 which extend laterally outwardly from and are rigidly secured to the arm 32. The lower end of the sleeve 48 is provided with a diametrically enlarged head 53 having axially outwardly projecting clutch teeth or the like 54. The side or working faces of the teeth 54 diverge in a direction axially outwardly of the head 53 whereby to cooperate with the side or working faces of clutch teeth 38 of the sleeve 37 when shiftable member 47 is moved downwardly into clutching engagement therewith. By reference to Fig. 3, it should be obvious that the corresponding divergence in the working faces of the cooperating clutch teeth 38 and 54 will tend to hold the clutch elements 37 and 53 in operating engagement during operation of the press, once they have been moved into clutching engagement.

The axially outer or upper end of the sleeve 75

48 is provided with an enlarged head 55 constructed in the same manner as the head 53 and having clutch teeth 56 extending upwardly therefrom, the side or working faces of the teeth diverging in a direction axially outwardly of the sleeve 48 or in an opposite direction from the working faces of the teeth 54 on the head 53. The clutch teeth 56 are adapted to have intermeshing engagement with cooperating teeth 57 which project axially outwardly or downwardly from an enlarged head 58 on a tubular sleeve 59. The teeth 57 engage the teeth 58 in the same manner as heretofore described in connection with the teeth 54 and 38 whereby to cause the clutch elements 55 and 58 to be held in operative engagement during rotation thereof when the shiftable member 46 is moved toward the sleeve 59. The sleeve 59 is mounted in spaced anti-friction bearings 60 carried one each by one of a pair of vertically spaced bearing brackets 61 extending laterally outwardly from and secured to the upper end of the arm 32. By reference to Figs. 1 and 3, it will be seen that the sleeve 59 is in radially outwardly spaced concentric relation to the spindle 29 and in axial alignment with the sleeve 36 and the shiftable member 47.

Means for imparting rotary movement to the sleeve 59 comprises transmission mechanism operatively associated with the stepped cone pulleys 42. A jackshaft 62 is journalled in spaced bearing brackets 63 and 64 rigidly secured to the arm 32. A pair of endless V-belts runs over a pair of relatively small flights 66 on the stepped cone pulley 42 and a relatively large double pulley 67 fast on one end portion of the jackshaft 62. A second pair of endless V-belts 68 runs over a relatively small diameter double pulley 69 fast on the upper end portion of the jackshaft 62 and a relatively large diameter double pulley 70 secured fast to the sleeve 59 by a set screw or the like 71. From the above it should be obvious that the relative diameters of the flights 66 and pulleys 67 causes the jackshaft to be rotated at various speeds slower than the various speeds of the cone pulley 42; and that the relative diameters of the pulleys 69 and 67 causes rotation of the sleeve 59 at a lower speed than that of the shaft 62. The relative diameters of the various pulleys provide for a maximum speed of the sleeve 59 slower than the minimum speed of the sleeve 36. By this means a pair of separate speed ranges is obtained in the spindle 29, thus doubling the flexibility of the drill press and the capacity thereof for different drilling operations.

I provide means for shifting the shiftable member 46 from a neutral position shown in Figs. 1 and 3 to a clutch-engaged position with either the relatively high speed sleeve 36 or the relatively slow speed sleeve 59. This means comprises a shifter lever or fork 72 equipped with a pair of axially aligned axial rollers 73 working in a circumferentially extended groove 74 in the shifter collar 49. The shifter fork 72 is pivotally mounted by means of a washer equipped bolt 75 extending therethrough into a mounting plate or the like 76 welded or otherwise secured to a pair of fingers 77 extending laterally outwardly one each from each of the bearing brackets 52. A pair of friction washers 78 made from any suitable material having a relatively high coefficient of friction are utilized to maintain the shifter fork 72 and shiftable member 46 in desired set position, see particularly Fig. 4. The shifter fork 72 is extended at its free end to provide a

handle 79 which extends laterally outwardly through an opening 80 in a housing or the like 81 mounted on the head structure 5.

From the above it should be obvious that when it is desired to operate the drill press in the low speed range, it is but necessary to manually move the handle 79 in a direction to cause the clutch teeth 56 to operatively engage the clutch teeth 57. On the other hand, when it is desired to operate the drill press in the high speed range, the handle 79 is moved in the opposite direction to cause the clutch teeth 54 to engage the teeth 38.

My invention has been thoroughly tested and found to be completely satisfactory for the accomplishment of the objectives set forth; and while I have shown a commercial embodiment of my improved drill press structure, it should be obvious that same is capable of modification without departure from the spirit and scope of the invention as defined in the claims.

What I claim is:

1. In a device of the class described, a head structure, a spindle mounted for rotary movements in said head structure, a drive shaft, a sleeve journaled for rotation in said head structure and concentric with said spindle, variable speed power transmission means associated with said drive shaft and sleeve for transmitting rotary movement to said sleeve at various speeds within a predetermined speed range, a second sleeve journaled for rotation in said head structure in axially spaced relation to said first mentioned sleeve and concentric with said spindle, power transmission mechanism operatively associated with said first and second sleeves whereby rotary movements are imparted to said second sleeve at various speeds within a speed range different from the range of speed of rotary movement of said first mentioned sleeve, opposed clutch elements on adjacent ends of said sleeves, and a shiftable clutch member keyed to said spindle for axial sliding movements with respect thereto into and out of driving engagement with either of said clutch elements independently of the other, whereby to impart rotary movements to said spindle in a selected speed range.

2. In a device of the class described, a head structure, a spindle mounted for rotary and axial movements in said head structure, a drive shaft, a sleeve journaled for rotation in said head structure and concentric with said spindle, variable speed power transmission means associated with said drive shaft and sleeve for transmitting rotary movement to said sleeve at various speeds within a predetermined speed range, a second sleeve journaled for rotation in said head structure in axially spaced relation to said first mentioned sleeve and concentric with said spindle, power transmission mechanism operatively associated with said first and second sleeves whereby rotary movements are imparted to said second sleeve at various speeds within a speed range different from the range of speed of rotary movement of said first mentioned sleeve, opposed tooth-equipped jaw clutch elements on adjacent ends of said sleeves, the working faces of the teeth of said clutch elements diverging in a direction axially outwardly of said sleeves, a shiftable member keyed to the spindle intermediate said sleeves for axial sliding movements with respect thereto, said shiftable member having a plurality of circumferentially spaced teeth at its opposite ends, the working faces of said teeth diverging in a direction corresponding

to the working faces of said clutch elements, whereby to prevent accidental disengagement of the teeth of said shiftable member from the clutch element engaged thereby, and means for moving said shiftable member into and out of clutching engagement with said clutch elements.

3. The structure defined in claim 2 in which the means for moving said shiftable member comprises a hand lever pivoted to said head structure, a shiftable collar on said shiftable member and engageable with one end of said lever, and friction elements between said lever and the head structure for frictionally holding said lever and shiftable member in desired set position.

4. In a device of the class described, a drill-head structure, a spindle mounted for rotary and axial movements in the head structure, a drive shaft in spaced parallel relationship to said spindle, a sleeve journaled for rotation in said head structure and concentric with said spindle, cooperating stepped cone pulleys on said drive shaft and said sleeve, an endless belt running over corresponding steps on said pulleys and shiftable thereon to vary the speed of rotation of said sleeve with respect to the drive shaft within a predetermined speed range, a second sleeve journaled for rotation in said head structure in vertically spaced axial alignment with said first mentioned sleeve and concentric with said spindle, a jackshaft journaled in said head structure in spaced parallel relation to said spindle and sleeves, cooperating pulleys fast on said sleeves and said jackshaft, endless belts running over said pulleys whereby to drive said jackshaft from said first mentioned sleeve and to drive said second sleeve from said jackshaft, the relative sizes of said pulleys effecting various speeds of rotation of said second sleeve in a speed range different from that of the first mentioned sleeve, opposed clutch elements on adjacent ends of said sleeves, a shiftable clutch member keyed to said spindle for axial sliding movements with respect thereto into and out of driving engagement with either of said clutch elements independently of each other whereby to impart rotary movements to said spindle in a selected speed range, and means for moving said shiftable member into and out of clutching engagement with said clutch elements.

5. The structure defined in claim 4 in which the opposed clutch elements on said sleeves comprise axially projecting teeth which are adapted to engage cooperating teeth on opposite ends of said shiftable member, the working faces of the teeth of said clutch elements diverging in a direction axially outwardly of the sleeves, the working faces of the teeth in said shiftable member diverging in a direction corresponding to the working faces on the teeth on said clutch elements, whereby to prevent accidental disengagement of the teeth of said shiftable member from the clutch element engaged thereby.

6. The structure defined in claim 4 in which the means for moving said shiftable member comprises a hand lever pivoted to said head structure, a shiftable collar on said shiftable member and engageable with one end of said lever, and friction elements between said lever and the head structure for frictionally holding said lever and shiftable member in desired set positions.

FRED L. NICHOLS.
